Primary Examiner — Mehri F Bajoul(74) *Attorney, Agent, or Firm* — Hanrahan Law Firm,
 P.A.; Benjamin M. Hanrahan(57) **CLAIM**

The ornamental design for an athletic training apparatus as shown and described.

DESCRIPTION

FIG. 1 is a front perspective view illustrating the design for an athletic training apparatus.

FIG. 2 is a front view thereof.

FIG. 3 is a rear view thereof.

FIG. 4 is a right-side view thereof.

FIG. 5 is a left-side view thereof.

FIG. 6 is a top view thereof; and,

FIG. 7 is a bottom view thereof.

The broken lines in the drawings illustrate seams of the athletic training apparatus that form no part of the claim.
